CABINET FOR A TELEPRINTER

Gary T. Panzica, 145 Metropolitan Drive
Rochester, N.Y. 14620

Filed Feb. 9, 1973, Ser. No. 331,015

Term of patent 14 years

Int. Cls. D6—04; D14—03
U.S. Cl. D6—173

FIG. 1

FIG. 2

FIG. 3

FIG. 4

FIG. 1 is a perspective view of a cabinet for a teleprinter showing my new design;

FIG. 2 is a right side elevational view;

FIG. 3 is a rear elevational view; and

FIG. 4 is a bottom plan view.

I claim:

The ornamental design for a cabinet for a teleprinter, substantially as shown and described.
